ADDRESSING MACHINE AND INKING MECHANISM THEREFOR

Harmon P. Elliott, Watertown, Mass.

Application February 11, 1935, Serial No. 5,945

21 Claims. (Cl. 101—48)

This invention relates to printing machines, as addressing machines, of the type wherein the data to be printed is carried by a succession of printing devices, as stencils, that are moved successively through the printing position.

The invention is particularly adapted to an addressing machine having a flat impression plate that reciprocates or, especially, swings into and out of pressure engagement with the successive stencils.

One of the objects of the present invention is the provision of an improved form of mechanism for supplying ink to the pressure face of the impression plate, particularly where the supply of ink comes from the surface of an ink bearing cylinder or drum located above the impression plate.

A further object of the invention is the provision of an inking mechanism for a reciprocable flat impression plate, the mechanism including an inking roller and means responsive to the reciprocatory movements of the impression plate for causing the roller to roll over the working face of the impression plate during the reciprocatory movements of the plate.

A yet further object of the invention is an improved form of mechanism wherein the ink roll is caused to traverse the working face of the plate from one end to the other thereof and into a position entirely clear of said plate and in engagement with ink transferring rolls during one of the strokes of the plate and to move across said face and deposit ink thereon during the other stroke of the plate.

A further object is generally to improve the construction and operation of inking mechanisms for flat impression plate addressing machines.

The inking mechanism herein described and claimed is described in my copending applications Serial No. 697,407, filed November 10, 1933, and Serial No. 5,944 filed February 11, 1935.

Fig. 1 is a transverse sectional view of an addressing machine embodying the present invention.

Fig. 2 is a sectional detail similar to Fig. 1 but with the parts in printing position.

Fig. 3 is a perspective detail of one side of the mechanism controlling the movements of the ink roll.

Fig. 4 is a front elevation of the inking mechanism of Fig. 1.

Fig. 5 is a plan view of the printing head, the parts normally disposed thereabove being removed.

Fig. 6 is a sectional detail of the printing head taken along line 6—6 of Fig. 5.

Fig. 7 is a sectional detail taken along line 7—7 of Fig. 4.

Fig. 8 is a perspective view of the supporting arm of the ink roll frame.

Fig. 9 is a perspective view of an operating link for the ink roll frame.

The addressing machine embodying the present invention includes a horizontal table 12 having a pair of horizontally spaced rails 14 that also are vertically spaced above the table and constitute a track in which the printing devices as stencils 16 are advanced in successive order into and out of the printing operation. 10 The printing mechanism includes an anvil or platen 18 having rearwardly extended arms 20 pivoted to a bracket 22 secured to the underside of the table. The anvil 18 is reciprocable vertically through an opening in the table into an operative position where it holds a work sheet 20 against a printing device 16. The anvil is reciprocated by means of a cam arm 24 having a cam face 26 that rolls under a cam roll 28 of the platen. The cam arm 24 is fixed to a shaft 30 journaled in the bracket 22. The shaft 30 is oscillated by an arm 32 that is fixed on the shaft and has a latch connection 34 with an operating segment 36 that is journaled on said shaft and is reciprocated from a power plant not shown through a connecting rod 38. 30

The printing head is carried by a horizontal frame 40 in the form of a loop pivoted at 42 to the bracket 22 above the top of the table 12. The frame 40 has a depending arm 44 that is connected through a toggle link 46 with the arm 32 so that the printing frame and anvil are reciprocated conjointly. The printing frame 40 has a pair of spaced arms 48 that are extended forwardly and have forward ends that overlie the stencil track 14. A pair of upper and lower horizontal rods 50 and 52 respectively are extended between and are carried by the forward ends of said arms and support a printing head. The printing head includes a pair of bracket arms 54 which are disposed within and close to the confronting faces of the arms 48 and on both of said rods 50 and 52, so that the bracket arms 54 are in effect rigid with said arms 48. An impression pad or plate holder in the form of a plate 56 is located under said bracket arms 54 and has upwardly extended ears 58 that are journaled on said lower rod 52 so that said holder plate is capable of swinging on said rod. Each bracket arm 54 has a pair of screws 60, 62 55

which are engaged with the holder plate 56 for the purpose of levelling the plate with respect to the printing devices. The screw 60 is passed loosely through the bracket arm and is screw-threaded into the holder plate 56. The screw 62 is screw-threaded in the bracket arm and bears upon the plate 56. Thus by proper adjustment of the screws the plate holder 56 can be levelled and at the same time fixed rigidly in position with respect to the bracket arms.

The plate holder 56 is provided with a dove-tailed groove 64 in its lower face in which an impression pad or plate 66 is removably retained. Said impression pad comprises a metal plate 68 slidable in the dove-tailed groove 64 and having on its lower surface an impression pad 70 of some resilient material as a rubber compound. The lower surface 72 of said pad is flat and is adapted to bear against the stencils 16 and to force ink from its surface through the type characters of the stencil and deposit the ink on the work sheet held therebeneath. The surface 72 of the impression pad, as here shown, is substantially co-extensive in width with the width of the data carrying face of the stencil, although in my copending application Serial No. 5,944 above referred to, a portion of the impression face is cut away so that a portion only of the total data carried by the stencil is printed. The impression pad is provided with a handle 74 at its front edge, which handle is adapted to enter a notch 76 in the front edge of the plate holder 56. The handle projects above the plate holder and forms manual means by which the impression pad may be applied to and removed from the plate holder. The plate holder is provided with a locking pin 78 that is adapted to enter a recess in the plate 68 of the impression pad, being removably held in said recess by a leaf spring 80 whereby releasably to lock the pad in the holder. The forward end of the leaf spring projects above the top face of the plate holder and in a position to be engaged and raised readily by a finger in the act of withdrawing the impression pad.

The inking mechanism for the impression pad includes a large ink distributing roll or drum 82 located above the printing head between the arms 48 and secured to a shaft 84. Said shaft is journaled in bearing brackets 86, see especially Figs. 5 and 7, secured to the forward ends of a pair of stationary arms 88 attached at their rear ends to a bracket 90 carried by the frame of the machine. An ink reservoir or fountain in the form of a cylinder 92 having a perforated side wall is journaled in the upper end of a swinging frame 94, the lower end of which is pivoted at 96 to the bracket 90. A transfer roll 98 is journaled in the upper end of said frame and is in rolling contact with the ink reservoir 92. A spring 100 bears against said frame 94 and urges it for rotation in a counterclockwise direction, Fig. 1, whereby to hold the roll 98 in rolling contact with the periphery of the drum 82. The roll 98 is rotated continuously by means including a belt 102 and thereby continuously drives the drum 82. The roll 98 in its rotation is reciprocated axially by means including the gearing 104 now well known in the art.

Ink is transferred from the distributing drum 82 to the vicinity of the impression plate or pad by means including a series of contacting transfer rolls 106, 108, 110. Said rolls are journaled on rods 112, 114 and 116, respectively, which are extended between and carried by normally depending arms 118, the upper ends of which are dis-

posed between the aforesaid arms 88 and are journaled upon the inner ends of shoulder screws 120. The upper two rods 112, 114 are loosely disposed in longitudinal slots 121 of said arms so that the rolls are free to move lengthwise thereof while the rod 116 for the lowermost roll is fixed in said arms against displacement. Tensile springs 122 are connected to said arms and to the stationary supporting arms 88 and urge said roll carrying arms for rotation in a counterclockwise direction, Fig. 1, so as to hold the transfer rolls in engagement with each other and with the uppermost roll in rolling engagement with the drum 82. Said arms 118 are provided with rearwardly extended projections 119 which are adapted to confront screws 87 adjustably screw-threaded in the bearings 86 for the distributing drum shaft whereby to limit the clockwise rotation of said arms under urge of the springs 122. The diameter and arrangement of the rolls are such that the lowermost rolls are thus held by the springs 122 in close proximity with the forward edge of the impression plate, as illustrated in Fig. 1. Since all of the transfer rolls are in engagement with each other the rotation of the drums maintains the rolls in continuous rotation. When access to the printing head is desired for the purpose of changing impression plates or the like the arms 118 with their rolls can be raised into the position illustrated in the dotted lines, the springs 122 moving across the centers of the screws 120 and holding the arms and rolls releasably in their out of service position.

Ink is transferred from the lowermost transfer roll 110 to the impression face of the impression plate by means including an inking frame having a pair of side arms 124, see Figs. 1, 3 and 8. Said arms are disposed outside the supporting arms 48 for the printing head and also outside the stationary arms 88 and have their upper ends pivoted on the shoulder screws 120. Plates 126 are disposed within said arms and are pivotally connected to the lower ends thereof by screws 128. Said plates extend forwardly and are connected at their forward ends by a rod 130 on which a rotatable inking roll 132 is supported, said roll being disposed beneath and adapted to roll forwardly and backwardly over the impression face of the impression pad to and from a contacting position with the lowermost transfer roll 110 thereby to deposit ink upon the surface of the impression pad. The side plates 126 are spring-biased for rotation in a clockwise direction, Fig. 1, thereby to hold the inking roll 132 in rolling contact with the surface of the impression pad by tension springs 134. One end of each of said springs is connected to the arm 124 and the other end is connected to a finger 136 which is secured to its respective side plate 126 by a screw 138 and a pin 140. The side plates have projecting stop pins 142 which are adapted to bear against the forward edges of the arms 124 to limit the rotational movement of the side plates under urge of the springs 134 when the inking roll 132 is free from engagement with the impression plate.

The inking frame is adapted to be moved forwardly into the position illustrated in Fig. 2 for the purpose of applying ink from the lowermost transfer roll 110 to the inking roll 132, at the time the printing head is in engagement with the stencil and thus is materially below the inking roll. It would be undesirable to have the inking roll pass over the front face of the impression pad and its holder 64 and hence means are provided

to keep the ink roll out of contact with these faces during the time that the ink roll is forward thereof and the impression head is rising and falling in back of the roll. Said means includes 5 cam plates 144 secured to the opposite side faces of the plate holder 64. Said cam plates have flat lower cam surfaces 146 and front ends 148 that project forwardly of the front faces of the impression plate and its plate holder and have lower 10 and upper inclined faces 150 and 152, respectively. The heads 154, see Figs. 1, 2, 4 and 8, of the screws 138 project from the inner faces of the side plates 126 and are adapted to bear against the cam faces of said cam plates in the movement 15 of the printing frame. The arrangement is such that ordinarily the heads 154 of the screws are out of contact with the lower straight faces 146 of the cam plates so that the ink roll can be held by the springs 134 in rolling contact with the face 20 of the impression plate. Said heads, however, are adapted to engage the forward ends of the cam plates in the forward position of the inking frame and especially as the printing head moves downwardly and upwardly so as to hold the inking roll 25 out of engagement with the front faces of the impression plate and its plate holder.

The reciprocation of the inking frame is effected by the reciprocation of the printing head. On each side of the printing head there is a link 30 156, see Figs. 1, 2, 3 and 9. The lower end of the link is pivoted on a screw 158 secured in the forward end of a bracket arm 54 of the printing head. Said link extends upwardly and overlies the outer face of the arm 124 of the inking frame 35 in the rear of the pivot screw 120. The upper portion of said link is provided with a longitudinally elongated slot 160 therein. A slide block 162 is located in said slot 160 and is pivoted on a screw 164 carried by the arm 124. A screw 166 is 40 adjustably screw-threaded in said link below said slide block 162 and in position at times to bear against the lower face of said slide block. Said link 156 is also provided with a cam roller 168 which is disposed beneath and is adapted to 45 cooperate with an inclined cam face 170 formed on the front edge of the arm 124. The arrangement is such that the reciprocatory movements of the printing head control the movements of the inking frame. The inking frame is urged for rotation in a clockwise direction by tensile springs 172, the forward ends of which are connected with the upper ends of said arms and the rear ends of which are connected to the stationary supporting arms 88. Thus the slide blocks are 50 maintained in engagement with the upper ends of the screws 166 or the cam faces 170 of the arms 174 are maintained in engagement with the cam rollers 168 of the links 156, as the case may be depending upon the setting of the screws 166. 55 On the downward movement of the printing head the links 156 move so correspondingly downward and thus the arms 124 are permitted to move forward under action of the springs 172, thus causing the inking roll 132 to advance across the impression face of the ink pad and ultimately into 60 position in engagement with the lowermost transfer roll 110. Movement of the inking frame in a forward or clockwise direction is limited by screws 174 screw-threaded adjustably in the upper ends of the arms and overlying the upper faces of the supporting arms 88. The movement of the inking frame into the aforesaid relation takes place during the first part of the downward 65 or working stroke of the printing head. In the 70 upward movement of the printing head the cam 75

roller 168 or the adjusting screw 166 or both engage the arms 124 and retract the inking frame, thereby causing the ink roll to rotate over across and in engagement with the impression face of the impression plate. The adjusting screw 166 5 ordinarily is so set that the major portion of the swinging movements of the arms 124 is under control of the cam rollers 168. During the final part of the retraction movement of the inking frame, however, the setting of the screws 166 is 10 such as to engage the slide blocks 162 and thereby move the inking frame and thereby retract the inking frame into a definite position as determined by the setting of the screws.

I claim:

1. In an addressing machine having a flat reciprocable impression plate, an ink bearing roll disposed at one side of said impression plate, a swinging inking frame, an inking roll carried by said frame and movable across and in contact with the impression face of said plate and into and out of engagement with said ink carrying roll; means for reciprocating said plate, and means for moving said inking roll across said plate in timed relation to the movements of said plate comprising a control link having a pivotal connection for one end thereof with a reciprocating part of said plate and having means providing a combined sliding and pivotal support for its other end, and means cooperating between said link and frame controlling movements of said frame through said link.

2. In an addressing machine having a reciprocable printing head bearing a flat faced impression plate that is detachable from said head in 35 a direction toward the front thereof, an ink carrying roll disposed in front of said head and plate, an inking roll movable in timed relation with the movements of said head across and in contact with the face of said impression plate 40 and into and out of engagement with said ink carrying roll; means for supporting said ink carrying roll removably in the aforesaid relation, permitting it to be moved from the path of detaching movement of said plate.

3. An addressing machine comprising a reciprocable printing head having a flat faced impression plate, an ink carrying roll disposed at one side of said plate, an inking roll movable across the face of said impression plate and into and out of engagement with said ink carrying roll, in combination with means to effect the movements of said printing head and inking roll in timed relation with each other including a swinging frame supporting said inking roll, and a link having a pivotal connection with said head and a sliding and pivotal connection with said frame, and cooperating frame-movement governing means on said frame and link.

4. In an addressing machine the combination 60 of a reciprocable printing head having a flat faced impression plate, an inking mechanism for the face of said plate comprising a rotatable ink distributing drum disposed above said head, means for supplying ink to the periphery of said drum, a pivoted ink transfer frame depending below said drum, a plurality of transfer rolls rotatable on said frame in rolling contact with each other and one with said drum, and an inking roll movable across and in rolling contact with 65 the face of said impression pad and into and out of engagement with the lowermost one of said rolls.

5. An addressing machine as defined in claim 4, the lowermost transfer roll of said inking trans- 75

fer frame being rotatably supported in said frame against displacement in a radial direction and said other rolls being mounted for radial displacement in said frame.

5 6. An addressing machine as defined in claim 4, having spring means to urge said frame in a direction to maintain the uppermost transfer roll in rolling engagement with said distributing drum, and said distributing drum thereby defining 10 the position of said frame.

7. An addressing machine as in claim 4, means including an over-center spring urging said frame for rotation in a direction to maintain said uppermost transfer roll in engagement with said 15 distributing drum, said drum thereby defining the operative position of said frame, said frame being capable of being swung upwardly about its pivot to move said over-center spring across the pivotal center and said spring constituting 20 means to maintain said uppermost transfer roll against said distributing drum, whereby to define the elevated position of said ink transfer frame.

8. In an addressing machine having a reciprocable printing head bearing a flat faced impression plate, an inking mechanism therefor comprising a swinging inking frame having a fixed pivotal support for its upper part, a roller rotatable on the lower part of said frame, said frame and roller being arranged for swinging movement 25 to reciprocate said inking roll across and in contact with the impression face of said impression plate, means to supply ink to said roll at a predetermined position thereof; link means interconnecting said head and frame and having a 30 sliding connection with said frame and governed by the reciprocatory movements of the printing head to effect the reciprocatory movements of 35 said inking frame.

9. In an addressing machine having a reciprocable printing head bearing a flat faced impression plate, an inking mechanism therefor comprising a swinging inking frame having a fixed pivotal support for its upper part, an inking roll rotatable on the lower part of said frame, said 40 frame and roll being arranged for swinging movement to reciprocate said inking roll across and in contact with the impression face of said impression plate, means to supply ink to said roll at a predetermined position thereof; means governed by the reciprocatory movements of the 45 printing head to effect the reciprocatory movements of said inking frame, said means including a spring normally urging said frame for movement in one direction, and link means directly interconnecting said head and frame and having a 50 sliding connection with said frame and movable with said printing head controlling the action of said spring in moving said inking frame in one direction and moving said frame against the action of said spring in the opposite direction.

60 10. An addressing machine comprising the combination of a reciprocable printing head having a flat faced impression platen, an inking mechanism therefor including a swinging inking frame having side arms, fixed pivotal supports for the upper ends of said side arms, plates pivoted to the lower end of said side arms, an inking roll carried by and disposed between and 65 journalled on said side plates, spring means urging said plates and inking roll in a direction to urge said roll in engagement with the impression roll of said impression pad, means for reciprocating said frame to carry said roll across and in 70 engagement with the face of said impression plate,

and means to apply ink to said inking roll at a predetermined location thereof.

11. An addressing machine as defined in claim 10 including means governed by the movements of said printing head to effect the reciprocation 5 of said printing inking frame.

12. An addressing machine comprising the combination of a reciprocable printing head having a flat faced impression pad, an inking mechanism therefor comprising a swinging inking frame 10 having a pivotal support for its upper end, side plates having a pivotal connection with the lower end of said frame, an inking roll journalled on said side plates, spring means urging said side plates and inking roll toward a predetermined position, said printing head having cam plates and said side plates having cam followers movable over the cam faces of said plates, said cam plates and cam followers defining the position of said inking roll with respect to the inking face of 20 said pad, and means to apply ink to said inking roll at a predetermined location thereof.

13. An addressing machine comprising the combination of a reciprocable printing head having a flat faced impression pad, an inking mechanism therefor comprising a swinging inking frame having a pivotal support for its upper end, side plates having a pivotal connection with the lower end of said frame, an inking roll journalled on said side plates, spring means urging said side plates 30 and inking roll toward a predetermined position, said printing head having cam plates and said side plates having cam followers movable over the cam faces of said plates, said cam plates and cam followers defining the position of said 35 inking roll with respect to the inking face of said pad, said inking roll being movable into a position in front of the front face of said impression plate, said cam plates having the forward ends projecting forwardly of the front face of 40 said impression plate and so shaped as to maintain said inking roll out of contact with the front face of said impression plate, and an ink transfer roll disposed in front of said printing head in position to be engaged by said inking roll. 45

14. An addressing machine having a supporting frame, a reciprocable printing head bearing a flat faced impression plate, an inking mechanism therefor comprising an inking frame having a pivotal support on said supporting frame, an inking roll reciprocable across the face of said impression plate; means including a control link having a pivotal connection with said head and cam engagement with said inking frame and operated by said head for effecting the reciprocatory 55 movements of said inking frame.

15. An addressing machine having a machine frame, a reciprocable printing head bearing a flat faced impression plate, an inking frame pivoted to a stationary part of said machine frame 60 and having an inking roll reciprocable with said frame across the face of said impression plate, spring means connected with said frame for urging it for movement in one direction; means including a control link having a pivotal connection with said head and cam engagement with said inking frame and reciprocable with said inking frame for controlling the spring urged movement of said inking frame and for moving said inking frame in the opposite direction against 70 the action of said spring.

16. An addressing machine having a machine frame, a reciprocable printing head bearing a flat faced impression plate, an inking frame pivoted to a stationary part of said machine frame 75

and having an inking roll reciprocable with said frame across the face of said impression plate, spring means connected with said frame for urging it for movement in one direction; a link carried by and reciprocable with said printing head engageable with said printing frame and operative to control its movements in one direction and to move it in the opposite direction, said link having a lost motion connection with said inking frame.

17. An addressing machine having a machine frame, a reciprocable printing head bearing a flat faced impression plate, an inking frame pivoted to a stationary part of said machine frame and having an inking roll reciprocable with said frame across the face of said impression plate, spring means connected with said frame for urging it for movement in one direction; a link carried by and reciprocable with said printing head and having a lost motion connection with said inking frame and with said machine frame and operative to control the movements of said inking frame in one direction and to move it in the opposite direction, said inking frame having a cam face and said link having a cam follower engageable with said cam face to control the movements of said frame.

18. An addressing machine comprising the combination of a reciprocable printing head having a flat faced impression pad, an inking mechanism therefor including a swinging inking frame having an inking roller reciprocable against and in contact with the impression face of said impression plate, and means governing the movements of said inking frame including spring means acting on said frame for moving it in one direction, a link reciprocable with said printing head having a longitudinally elongated slot therein, a slide block in said slot carried by said frame, and a member screw-threaded in said link adapted to bear against said slide block, said inking frame being movable under the action of its spring in one direction under control of said link and being moved positively in the opposite direction against the action of its spring by said link.

19. An addressing machine comprising the combination of a reciprocable printing head having a flat faced impression plate, an inking mechanism therefor comprising an ink distribut-

ing drum rotatable above said printing head, means for applying ink to the face of said drum, an ink transfer frame disposed below said drum in front of said head having a series of peripherally contacting transfer rolls the uppermost one of which is in rolling contact with said drum, an inking frame having an inking roller reciprocable across and in contact with the impression face of said impression plate and into and out of engagement with the lowermost transfer roll of said series, a link pivoted to said printing head and reciprocable therewith, and operative connections between said link and inking frame for controlling the reciprocatory movements thereof.

20. An addressing machine comprising the combination of a reciprocable printing head having a flat faced impression plate, an inking mechanism therefor comprising an ink distributing drum rotatable above said printing head, means for applying ink to the face of said drum, an ink transfer frame disposed below said drum in front of said head having a series of peripherally contacting transfer rolls the uppermost one of which is in rolling contact with said drum, an inking frame having an inking roller reciprocable across and in contact with the impression face of said impression plate and into and out of engagement with the lowermost transfer roll of said series, spring means connected with said inking frame for moving it in one direction and means including a link pivotally connected with said printing head and reciprocable therewith, said link having operative connections with said inking frame and operative to control its movement in one direction under the action of said spring and for moving said frame positively in the opposite direction against the action of said spring.

21. In an addressing machine, the combination of a reciprocable printing head having a flat faced impression plate, and inking mechanism for the printing face of said plate including a pivoted inking frame, and an inking roll for said plate carried by and having a yielding vertically swinging connection with the free end of said frame permitting said roll to rise and fall when traversing the face of said plate.

HARMON P. ELLIOTT. 50
